Primary Examiner — George D. Kirschbaum*Assistant Examiner* — Maria J Edwards(74) *Attorney, Agent, or Firm* — McDermott Will & Emery LLP(57) **CLAIM**

The ornamental design for a lounger, as shown.

DESCRIPTION

FIG. 1 is a top right front perspective view of a lounger showing my new design;

FIG. 2 is a front view thereof;

FIG. 3 is a rear view thereof;

FIG. 4 is a top plan view thereof;

FIG. 5 is a bottom plan view thereof; and,

FIG. 6 is a left elevation view thereof.

The broken lines shown in FIGS. 1, 2 and 4-6 form no part of the claimed design.

1 Claim, 5 Drawing Sheets(56)
